CLUTCH AND BRAKE FOR WASHING MACHINES

William G. Landwier, Fayetteville, N. Y., assignor to Easy Washing Machine Corporation, Syracuse, N. Y., a corporation of Delaware

Application July 20, 1950, Serial No. 174,979

6 Claims. (Cl. 192—12)

1

This invention relates to washing machines, and more particularly to a control for an agitator type washing machine.

In Geldhof Patent 2,111,143, and also application Serial No. 792,363, filed December 18, 1947, now Patent No. 2,627,175, there is shown a transmission and a control mechanism for applying power at will to a vertical oscillatory agitator such as is commonly used in washing machines. The control as shown acts to shift a constantly meshing pinion having a castellated end upon a vertical agitator shaft, the castellated end being adapted in one position to engage a transverse clutch pin mounted in the shaft. In the arrangement shown, the control rock shaft is held in either one or the other of two end positions by an over-center tension spring, and acts through a lost-motion crank arm and a vertically slideable rod on which the pinion engaging shifter yoke is positioned. Such arrangement comprises a number of parts, and has required for assembly purposes that the rock shaft be made in two pieces coupled together at a point adjacent to the lost-motion crank arm.

The present invention utilizes substantially the same principle of operation, but is specifically directed to a substantial reorganization of the parts, whereby the number of parts is reduced and the assemblage thereof is simplified. One feature of the invention is the utilization of a one-piece rock shaft so constructed as to enable quick assembly thereof in the mechanism. Another feature of the invention is the utilization of an over-center compression spring acting directly upon an arm forming an integral part of the rock shaft.

The above and other novel features of the invention will appear more fully hereinafter from the following detailed description when taken in conjunction with the accompanying drawings. It is expressly understood that the drawings are employed for purposes of illustration only and are not designed as a definition of the limits of the invention, reference being had for this purpose to the appended claims.

In the drawings, wherein like reference characters indicate like parts:

Figure 1 is a fragmentary transverse sectional view showing the transmission housing and the vertical agitator shaft emerging therefrom with the control rock shaft in position;

Figure 2 is a fragmentary sectional view taken through the rock shaft on the line 2—2 of Figure 1;

Figure 3 is a vertical sectional view taken substantially on the broken line 3—3 of Figure 1;

2

Figure 4 is a fragmentary vertical sectional view taken substantially on the broken line 4—4 of Figure 1, showing the rock shaft in drive position;

Figure 5 is a view similar to Figure 4, showing the rock shaft in disengaged or non-driving position; and

Figure 6 is a perspective view of a member forming an integral part of the rock shaft.

In the drawings, there is shown a transmission casing 10 having a main housing structure 12 which may be of a casting, and a top closure pedestal member 14, the latter being secured and seated in a large aperture in the top wall of the housing structure 12. Such pedestal member includes a substantially circular plate 16 adapted to cooperate with and form a closure for a corresponding enlarged aperture on the top wall of the casing structure 12, and has formed as a part thereof upstanding spaced members 18 and 20 which support a shouldered seat 22. The seat 22 has an upwardly extending threaded sleeve 24 which is adapted to project through a central aperture in a wash tub bottom wall 26, the threaded sleeve having a jam nut 28 adapted to clamp the tub bottom 26 between opposite washers 30 and 32. The sleeve 24 may be extended integrally or by a second sleeve 34 at the upper end of which is a sleeve bearing for the agitator drive shaft 36, such bearing being shown at 37. The agitator shaft 36 extends into a bearing boss 38 in the lower wall 40 of the transmission casing structure 12, and rests upon an end thrust ball 42. The plate 14 is provided with a clearance aperture 44 through which the shaft 36 extends, and the shaft is provided with a split thrust ring 46 lying in a groove 48, which ring bears against spacing washers 50 located thereabove and immediately below the plate 16.

Mounted upon the shaft 36 is a driven pinion 52 which is adapted to be constantly in mesh with a sector gear 54 that is given a to and fro motion by an eccentric or other mechanism. Such sector gear would be pivoted upon a vertical shaft journaled in a top bearing boss such as 55 in Figure 1, as is shown in the Geldhof patent or the application referred to. The pinion 52 is of sufficient breadth whereby it may be moved axially upon the shaft 36 without becoming disengaged, the pinion having a castellated end 56 adapted to engage the cross bar 58 passing through the shaft 36. Such castellated end engages the cross bar 58 for driving the shaft 36 when in the lower position shown, but by means of a yoke 60 riding in a groove 62 in the pinion hub, such pinion 52 may be lifted a sufficient distance

whereby to clear the cross pin 58 and thereby permit the pinion 52 to oscillate freely upon the shaft without driving the same. The yoke 60 is rigidly secure to a laterally spaced, vertically extending shifter rod 64 extending through a boss 66 in the plate 16. A compression spring is threaded upon the rod 64 and positioned between the boss 66 and the yoke 60, whereby to urge the yoke and the pinion 52 normally to a lower engaged position as is shown in Figure 3.

To actuate the shifter rod 64 and lift the same to an elevated position against the compression spring 68, there is provided a rock shaft 70, having thereon a rock arm 72, the latter extending into a bifurcated end 74 of the shift rod 64. Such rock arm 72 is provided with an elongated arcuate aperture 76, the end walls 78 and 80 of which are adapted to engage a transverse pin 82 extending across the bifurcated ends of the rod 64 and through the aperture 76. The rock arm 72 may be a part of a formed stamping, an arm 84 of which is provided with double bends 86 and 88, and a rock arm 90, both the rock arms 72 and 90 having apertures 92 and 94 through which the rock shaft 70 extends and to which the rock shaft is securely fixed as by welding, keying or otherwise.

The arm 90 is angularly directed so as to engage a cup 96 having a concave center section 98 and an annular skirt 100 within which one end of a compression spring 102 is seated. The other end of the compression spring 102 is seated upon a perch in the form of convex inclined projection 104 which may be formed integrally in the plate wall 16. The angle of the arm 90 is so disposed as to occupy an over-center position with respect to a line 106 extending from the center of the projection 104 and the center of the rock shaft 70, one over-center position being shown in Figure 4 and the other being shown in Figure 5. The lost-motion resulting from the arcuate aperture 76, and the over-center compression spring, provides snap action in engaging or disengaging the pinion with the cross bar 58.

Movement of the rock shaft 70 in the counterclockwise direction as viewed in Figure 5 is limited by the brake portion 108 between the bends 86 and 88 of the arm 84, such brake portion 108 being adapted to rest upon the shaft 36 and provides sufficient but light friction upon the shaft 36 whereby when the pinion 52 is disengaged from the cross arm 58, and oscillating freely upon the shaft, the shaft 36 will be held substantially stationary. The degree of friction resulting from the brake surface 108 may be controlled by the extent of the over-center position taken by the arm 90 when in the braking position as shown in Figure 5.

The rock shaft 70, as has previously been described, has positioned thereon the rock arms 72 and 90, the same being keyed or welded so as to form a unitary structure with the shaft 70. In order to position the shaft in the pedestal members 18 and 20, the member 20 may have a bearing aperture 110 and the member 18 an open half bearing slot 113 (see Figure 2). By such an arrangement, the shaft 70 may have its end 112 readily inserted into the aperture 110, the shaft being rested in the bearing recess 113, it appearing that the open bearing recess 113 permits such assembly with the rock arms 72 and 70 already rigidly secured to the shaft 70. It will be observed that the force exerted by the compression spring 102 is so directed as to hold the rock shaft 70 in the open bearing recess 113, 75

thereby permitting the assembly of the unitary rock shaft structure described. The end of the shaft 70 may project through an outer wall or skirt 114 having an aperture 116 in which there is fitted a grommet 118. The shaft may have a right angle bend as at 120 forming an offset means tending to prevent the threading of the shaft through a closed bearing, and a handle extension 122 to which may be applied a convenient knob 124, the latter being applied after assembly if desired, or being of a size sufficiently small to pass through the aperture 116 prior to the insertion of the grommet 118.

The shaft 36 is provided with a split ring 126 resting in a groove 128 above the plate 16, there being secured in position thereby an umbrella or slinger 130 to prevent entrance under any circumstances of water into the transmission 10.

It will thus be seen that the structure described is relatively simple and composed of few parts which may be quickly assembled and which, in assembly position, act directly upon the control mechanism for engaging or disengaging the castellated pinion from the cross bar of the agitator shaft. The strength of the compression spring 102 is such as to overcome at all times the strength of the compression spring 68 upon the rod 64. By reason of the toggle action between the compression spring 102 and the arm 90, the effectiveness of the spring 102 to overcome the spring 68 is readily accomplished.

Although a single embodiment of the invention has been illustrated and described, it is to be understood that the invention is not limited thereto. As various changes in the construction and arrangement may be made without departing from the spirit of the invention, as will be apparent to those skilled in the art, reference will be had to the appended claims for a definition of the limits of the invention.

What is claimed is:

1. In a control for a washing machine agitator drive, a vertical agitator shaft, a bearing member therefor, clutch means comprising an element affixed to and an element axially movable on the shaft for controlling operation of the agitator shaft, a slide member connected to said movable element for actuating the same, a transverse rock shaft having integral spaced arms and friction means adapted to engage said drive shaft, one being connected to said slide member and the other adapted to engage a compression spring, said rock shaft and arms being formed as a rigid unit, a compression spring lying on a line bisecting the normal angle of movement of the last-named arm having one end in engagement therewith and the other end in engagement with said bearing member, spaced bearings for said rock shaft on said bearing member on opposite sides of said spaced arms, one of said bearings being radially open on a side toward said compression spring whereby said spring holds said rock shaft seated in said open bearing.

2. In a control for a washing machine agitator drive, a vertical agitator shaft, a bearing member therefor, clutch means comprising an element affixed to and an element axially movable on the shaft for controlling operation of the agitator shaft, a slide member connected to said movable element for actuating the same, a transverse rock shaft having integral spaced arms formed from a double bent element having a braking surface adapted to engage said agitator shaft, one arm being connected to said slide-

able member and the other arm being adapted to engage a compression spring, said rock shaft and double bent element being formed as a rigid unit, a compression spring lying on a line bisecting the angle of normal movement of the last-named arm having one end in engagement therewith and the other end in engagement with said bearing member, spaced bearings for said rock shaft on said bearing member on opposite sides of said spaced arms, one of said bearings being radially open on a side toward said compression spring whereby said spring holds said rock shaft seated in said open bearing.

3. In an agitator drive shaft and control assembly, a housing cover plate, an agitator drive shaft extending through said cover plate, said shaft having a drive pinion on one side of said cover plate, and said cover plate having spaced walls extending therefrom on the other side, on either side of said shaft, and supporting a bearing for said shaft, a pinion sliding mechanism including a sliding member extending through said plate substantially parallel to and spaced from said drive shaft, a rock shaft journaled in said walls, extending transversely of said agitator shaft and between said agitator shaft and sliding member, rock arms integrally secured to said rock shaft between said walls forming an integral one-piece unit with the rock shaft, one of said arms being connected to said sliding member, a compression spring bearing against said other arm and a perch on said plate, and extending substantially along a center line between said perch and rock shaft intermediate the angle of movement of said other arm, whereby to provide a toggle-like over-center resilient means, and a brake member secured to said rock shaft and adapted to bear against said agitator shaft to brake said shaft, and limit movement of said rock shaft in one direction to define one limit of said angle of movement, means for limiting movement of said sliding member in one direction to define the other limit of said angle of movement of said rock shaft in the other direction, and bearings in said spaced walls for said rock shaft, one bearing being radially open on the side toward said compression spring, whereby assembly of the integral rock shaft and arms is facilitated and said rock shaft is held seated in said open bearing by said compression spring.

4. In an agitator drive shaft and control assembly, a housing cover plate, an agitator drive shaft extending through said cover plate, said shaft having a drive pinion on one side of said cover plate, and said cover plate having spaced walls extending therefrom on the other side, on either side of said shaft, and supporting a bearing for said shaft, a pinion sliding mechanism including a sliding member extending through said plate substantially parallel to and spaced from said drive shaft, a rock shaft journaled in said walls, extending transversely of said agitator shaft and between said agitator shaft and sliding member, rock arms integrally secured to said rock shaft between said walls, one of said arms being connected to said sliding member, a compression spring bearing against said other arm and a perch on said plate, and extending substantially along a center line between said perch and rock shaft intermediate the angle of movement of said other arm, whereby to provide a

toggle-like over-center resilient means, and a brake member secured to said rock shaft and adapted to bear against said agitator shaft to brake said shaft, and limit movement of said rock shaft in one direction, said arms and brake member formed of a single double bent stamping, the brake member lying between the adjacent bends, means for limiting movement of said sliding member in one direction to limit movement of said rock shaft in the other direction, and bearings in said spaced walls for said rock shaft, one bearing being open on the side toward said compression spring, whereby assembly of the integral rock shaft and arms is facilitated and said rock shaft is held seated in said open bearing.

5. A control rock shaft for an agitator drive control, comprising a shaft, a double bent stamping comprising spaced parallel arms lying in parallel planes transverse to said shaft, and an intervening integral connecting portion extending parallel with the shaft and spaced therefrom and having a braking surface adapted to extend substantially parallel to the shaft, said arms each having an aperture for said shaft spaced from said braking surface, and means for integrally securing at least one of said arms to said shaft.

6. In a control for a washing machine agitator drive, a vertical agitator shaft, a bearing member therefor, clutch means comprising an element affixed to and an element axially movable on the shaft for controlling operation of the agitator shaft, a slideable member connected to said movable element for axially actuating the same, a transverse one-piece rock shaft having an integral radial arm thereon located short of one end thereof, said arm being connected to said slideable member, said rock shaft having its other end extended from said arm and of substantially greater length than the first-named end, spaced bearings for said rock shaft on said bearing member, located on opposite sides of said arm, one of said bearings being radially open on one side for the lateral placing of a portion of the extended end of said shaft therein, and the other being closed and adapted to receive said one end of said shaft by endwise insertion thereinto, an integral radial arm on said shaft between said bearings projecting in a direction generally that of the radially open bearing, a compression spring aligned generally in the direction of said radially open bearing, and having one end bearing against the end of said last-named arm, and the other end bearing under compression against said bearing member to provide a resilient over-center knee action, and stop means for limiting rotation of said rock shaft, said stop means being adapted to limit rotation of the shaft to an angle including the over-center position of said last-named arm with respect to the compression spring.
